HOUSING FOR A GRANULAR MATERIAL DISPENSER

Raymond H. Gutzmann, 11917 Gerald Ave., Granada Hills, Calif., and John M. McGavin, 7437 Sylmar Ave., Van Nuys, Calif.

Filed Sept. 20, 1963, Ser. No. 76,651

Term of patent 14 years

(Cl. D4—3)

FIG. 1

We claim:

The ornamental design for a housing for a granular material dispenser, substantially as shown.
